UNITED STATES PATENT OFFICE.

HARRY C. GOWRAN, OF TWO RIVERS, WISCONSIN, ASSIGNOR TO THE HAMILTON MANUFACTURING COMPANY, OF TWO RIVERS, WISCONSIN, A CORPORATION OF WISCONSIN.

DESIGN FOR A CABINET.

45,623.

Specification for Design.

Patented Apr. 21, 1914.

Application filed February 16, 1914. Serial No. 819,120. Term of patent 7 years.

To all whom it may concern:

Be it known that I, HARRY C. GOWRAN, a citizen of the United States, residing at Two Rivers, in the county of Manitowoc and State of Wisconsin, have invented a new, original, and ornamental Design for Cabinets, of which the following is a specification, reference being had to the accompanying drawing, forming part thereof.

The drawing is a perspective view of a cabinet, showing my new design.

I claim:

The ornamental design for a cabinet as shown.

HARRY C. GOWRAN.
